UNITED STATES PATENT OFFICE.

WILLIAM W. WATSON, OF JAMESTOWN, NEW YORK.

METALLIC ROLLER.

1,287,152.

Specification of Letters Patent. Patented Dec. 10, 1918.

Application filed May 9, 1918. Serial No. 233,403.

To all whom it may concern:

Be it known that I, WILLIAM W. WATSON, a citizen of the United States, residing at the city of Jamestown, in the county of Chautauqua and State of New York, have invented certain new and useful Improvements in Metallic Rollers, of which the following, taken in connection with the accompanying drawings, is a specification.

10 The invention relates to metallic rollers for shelving and particularly for book shelves; and the object of the improvement is to provide a light and strong struck-up two-part sheet metal roller which has 15 strongly braced tubular end journal portions for rotative mounting on a shaft, the parts being so shaped and braced that the completed roller rotates easily when heavy books pass over the same and has a smooth 20 exterior which does not injure the books; and the invention consists in the novel features and combinations hereinafter set forth and claimed.

In the drawings, Figure 1 is a perspective view of the finished roller showing one of the tubular end bearings and the drainage holes in said end; and Fig. 2 is a sidewise elevation of the same. Fig. 3 is a sectional view at line 3—3 in Fig. 2 of the outer 25 casing of the roller, the interior radially bracing portion being shown in the position which it assumes when the two sheet metal parts are fully assembled into the finished roller by suitable dies. Fig. 4 is a crosswise 30 sectional view at line 4—4 in Fig. 2 showing the shape and radial arrangement of the inner bracing portion for the outer part. Fig. 5 is a plan view of the blank for the outer casing with the ends notched and shaped 35 for turning inwardly upon the tubular bearing portions of the inner part; and Fig. 6 is an elevation of the next step in forming the roller casing in which the blank shown in Fig. 5 is turned into a cylindrical tube 40 ready for the inward turning of the ends. Fig. 7 is a sidewise elevation and Fig. 8 is an endwise elevation of the struck up inner bracing or supporting portion for the outer cylindrical portion ready for insertion 45 in the casing tube shown in Fig. 6 showing the tubular bearings at each end and the lengthwise curved radial supporting bars for the inner walls of the cylinder. Figs. 50 5 and 10 show the preceding step in shaping the inner bracing portion to that shown in Figs. 7 and 8 with the cylindrical ends and

semi-circular bar portions in the U-shape ready for closure into the shape shown in Figs. 7 and 8. Figs. 11 and 12 show the preliminary step in the first step toward the 60 U-shaped struck up inner portion in which the flat lengthwise bars are given the semi-circular form and the flat end portions are started toward the complete cylinder. Figs. 13 and 14 show the flat sheet metal pattern 65 as struck out from a strip of metal ready for the steps shown in Figs. 7 to 12. Fig. 15 is an elevation of the finished roller rotatably mounted on its shaft which shaft is usually a part of the book shelf. 70

Like characters of reference refer to corresponding parts in the several views.

The numeral 20 designates the blank of flat sheet metal which forms the outer tube or casing portion, having V shaped notches 75 21 and U-shaped notches 22 in the ends thereof ready for turning into radial attachment over the inner portion of the two-part roller 23, the U-shaped notches forming drainage and ventilating holes 24 80 for the ends of the roller to prevent sweating and rusting, said blank 20 being struck up into a cylindrical roller casing or outer portion by suitable dies as hereinafter set forth. 85

The second or inner radial bracing portion 25, which is shaped in the finished roller as shown in Fig. 3 within the outer casing portion 20, is shown in its blanked out form 26 in Fig. 13, which blank 26 shows 90 the diminished end portions 27 which are shaped sufficiently narrow to permit their being upset or turning inward upon themselves under end pressure after being shaped 95 by suitable dies into the radially spaced position.

The shaping into the cylindrical form is attained by a series of steps. The first step in shaping after blanking out the form 26 is shown in Figs. 11 and 12, in which the end portions 28 are turned at their edges slightly 100 toward the desired tubular form. The central bar portions 29 are given their desired semi-cylindrical curved shape throughout their length while the narrowed portions 27 105 are bent to one side preparatory to being pressed as shown in Figs. 9 and 10 to their nearly full outward projection as they carry the curved bars 29, while the end portions 28 are turned into the U-shape shown in 110 Fig. 10. The next step toward the finished part 25 is the completion of the cylindrical

form for the tubular bearing ends 28, thereby at the same time correctly spacing the bar portions 29 so as to bear squarely against the inner walls of the cylindrical casing.

- 5 The next step in the formation of the roller 23 is the insertion of the inner bracing portion 25 shaped as shown in Figs. 7 and 8 within the tubular cylindrical portion 30 formed from the blank 20. The notched 10 end portions 21 and 22 of the cylindrical casing are crimped inward upon the tubular end portions 28 and said tubular end portions 28 are pressed inwardly toward one another within the cylinder 30 by means of 15 closure dies which fit over the ends of the roller 23, being shaped to guide the notched end portions 21 and 22 into exact contact with the outer ends of the tubular bearings 28 with radial contacting edges, with the exception of the U-shaped notches 22 which 20 form the drainage holes 24 as hereinbefore described. The narrowed parts 27 are upset upon themselves into the S-shape shown in Fig. 3 which up-setting of the three sheet 25 metal portions 27 at each end causes the three curved bar portions 29 to be pressed outwardly against the inner wall of the cylinder 30, bracing and interlocking both the parts of the roller into fixed alinement 30 from which they cannot be separated without destroying the roller.

The closure dies are so formed as to hold the tubular portions 28 firmly in their cylindrical form and press the same outwardly 35 on the crimped ends of the notched portions 21 and 22 of the cylinder 30 so that the sheet metal parts are actually driven into one another with a solidity which interlocks and prevents the separation or rattling of 40 said parts upon one another thereby making a roller of great rigidity out of sheet metal.

The interior supporting portion 25 is shaped with the lengthwise bars 29 bulging slightly at the center, as shown in Figs. 7 45 and 9, so that when said supporting portion 25, as shown in Fig. 7, is inserted into the cylindrical cover 30, as shown in Fig. 6, said supporting portion 25 will fit closely within said cover springing the same slightly 50 at the joint 31 so that when the diminished portions 27 at each end of each of the bars 29 are upset or caused to roll or fold inwardly in a continuous or consecutive bending movement throughout the length of said 55 diminished portion, each of the end portions of the bars 29 are forced outwardly against the inner wall of the cover portion 30 thereby holding the bearing ends or tubular portions 28 firmly in position as the notched 60 ends 21 and 22 are crimped onto the same and forming a solid coöperating whole out of the entire construction.

I claim as new:—

1. A metal roller composed of a cover and 65 a brace within the cover, the brace having

an integral bearing at each of its ends and the ends of the cover being extended inwardly to grip the peripheries of the respective bearings.

2. A metal roller composed of a cover and 70 a tubular brace therewith having integral bearings at its ends the latter projecting partly within and without the ends of the brace.

3. A metal roller comprising a cylindrical 75 cover portion, and an inner lengthwise portion for said cover portion comprising spaced bars supported on a bearing at each end.

4. A metal roller comprising a cover portion, an inner lengthwise bar portion, each of the lengthwise bars integral with a bearing part at each end and diminished adjacent thereto, said bearing parts pressed inward upsetting said diminished portion of 85 said bar and bracing said parts.

5. A metal roller comprising a round tubular cover portion having notched ends, slotted lengthwise bracing portions for said tubular cover portion, tubular bearing ends 90 for said bracing portion, said notched ends of said cover portion crimped onto said tubular bearing ends to hold said parts and close the ends of the roller.

6. A metal roller comprising a tubular 95 cover portion having notched ends, an inner portion consisting of spaced lengthwise bars having radial supports and bearing against the inner wall of said tubular cover portion, tubular bearing ends connected to said radial 100 supports for said bars to hold the same, said notched ends of said cover portion crimped onto said tubular bearing ends.

7. A metal roller comprising a tubular 105 cover portion, an inner portion consisting of spaced lengthwise bars curved in cross-section, tubular bearing ends for said inner portion connected to said curved bars to radially support the same, the ends of said tubular cover notched and crimped onto said tubular bearing ends of said inner portion, the connections between said tubular bearing ends and said curved bars being formed to press the curved sides of said curved bars against the inner wall of said tubular cover 110 portion.

8. A metal roller comprising a tubular covering portion having U and V-shaped notched ends to provide drainage openings by said U-shaped notches, an inner portion struck from one piece by suitable dies to form tubular end bearing portions and cross-wise curved lengthwise bar portions, the integral connecting portions between said curved bar portions and tubular end portions upset by suitable dies and said notched ends crimped by the same dies to unite said inner and outer portions into a complete roller by the movement of said dies toward one another.

9. A two-part sheet metal roller comprising a tubular cover part having notched ends, an inner portion having lengthwise slots therein and shaped to form tubular bearing ends for said roller, the connecting portions of said inner part between said tubular bearing ends shaped in crosswise curved lengthwise bars and extending outwardly to press against the inner wall of said tubular cover part, said connecting portions narrowed at each end and upset into S-shaped radial supports for said curved connected bar portions to support them against the inner wall of said tubular cover part, said notched ends of said tubular cover part crimped onto said tubular bearing ends of said inner part by the closure of the same dies that upset said inner part assembling all said parts into close alinement with drainage holes formed by the notches.

10. In a metal roller, a cover and a brace therein, said brace having bearings at its ends extending partly within and without the ends of the brace, the bearings being connected at their inner ends to the ends of the brace.

11. In a metal roller, a cover and a brace therein, said brace having bearings connected to its ends with the bearings extending partly within and partly without the brace ends, the cover having its ends turned inwardly to abut said bearing connections and the peripheries of the bearings.

12. A metal roller composed of a cover, a brace therein, bearings having their inner ends extending within the brace, the ends of

the cover being extended inwardly to engage and support the outer ends of the bearings, and means to support the inner ends of the bearings from the brace.

40

13. A metal roller composed of a cover, a brace therein, bearings borne by the brace, and connections for the bearings extending lengthwise of the brace and bearings and interposed therebetween.

45

14. A metal roller composed of a cover and a resilient brace, and means whereby to hold the end portions of the brace against the cover under tension.

15. In a metal roller, a cover, and a hollow sheet metal brace in the cover having integral tubular bearings at its ends.

50

16. In a metal roller, a cover, and a hollow resilient brace in the cover having integral tubular bearings at its ends.

55

17. In a metal roller, a cover, a hollow sheet metal brace in the cover, and integral bearings at the ends of the brace, the ends of the cover being extended inwardly to engage and support the bearings.

60

18. In a metal roller, a cover, and a hollow sheet metal brace in the cover, the ends of the cover being notched and crimped inwardly to form ends for the roller and to also form a ventilating opening communicating with the brace interior.

65

In testimony whereof I have affixed my signature in the presence of two witnesses.
